UNITED STATES PATENT OFFICE

155,024

DESIGN FOR A TOOL HOLDER OR THE LIKE

Ulysses S. Mozneck, Fairfield, Conn., assignor to Casco Products Corporation, Bridgeport, Conn.,
a corporation of Connecticut

Application June 29, 1948, Serial No. 147,275

Term of patent 14 years

(Cl. D80—9)

To all whom it may concern:

Be it known that I, Ulysses S. Mozneck, a citizen of the United States, residing at Fairfield, county of Fairfield, and State of Connecticut, have invented a new, original, and ornamental Design for a Tool Holder or the like, of which the following is a specification, reference being had to the accompanying drawing, forming part thereof.

The figure is a perspective view of a tool holder or the like, showing my new design.

I claim:

The ornamental design for a tool holder or the like, as shown.

ULYSSES S. MOZNECK.
